(57) **CLAIM**

The ornamental design for a stick for a hockey game table, as shown and described.

DESCRIPTION

FIG. 1 is a perspective view of a stick for a hockey game table showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view of the stick for a hockey game table, showing the design in use; and,

FIG. 9 is perspective view of a second embodiment of the stick for a hockey game table, the only difference being an electric board inserted therein.

The broken line showing is for illustrative purposes only, and forms no part of the claimed design.
